UNITED STATES PATENT OFFICE.

JOSEPH F. MERKEL, OF FLUSHING, NEW YORK.

LUBRICATING DEVICE FOR INTERNAL-COMBUSTION ENGINES.

1,280,267.

Specification of Letters Patent.

Patented Oct. 1, 1918.

Application filed December 23, 1915. Serial No. 68,345.

To all whom it may concern:

Be it known that I, JOSEPH F. MERKEL, a citizen of the United States, residing at Flushing, in the county of Queens and State 5 of New York, have invented certain new and useful Improvements in Lubricating Devices for Internal-Combustion Engines, of which the following is a specification, reference being had therein to the accompanying 10 drawings, forming part thereof.

My invention relates to lubricating devices for internal combustion engines and relates more particularly to lubricating devices for the internal combustion engines of 15 self-propelled vehicles of the comparatively small and light type commonly having two ground wheels in tandem. The self-propelled or motor vehicle in which my present invention is shown as embodied in the accompanying 20 drawings, is the same self-propelled vehicle which is illustrated and described and of which other features are claimed in two other applications for patent filed on even date herewith and designated 25 respectively as Serial Number 68,343 and Ser. No. 68,344, Ser. No. 68,343 relating more particularly to the vehicle controlling means and Ser. No. 68,344 relating more particularly to the transmission mechanism.

Objects of my present invention are simplicity and inexpensiveness of construction, effectiveness of operation, durability and continued maintenance in working condition, and other objects and advantages which will 30 hereinafter appear.

My invention includes features of construction and combinations of parts as will appear from the following description.

I shall now describe the lubricating device 40 embodying my invention illustrated in the accompanying drawings and shall thereafter point out my invention in claims.

Figure 1 is a transverse partly inclined and partly vertical section substantially on 45 the line 1—1 of Fig. 2 as viewed from the right.

Fig. 2 is an enlarged longitudinal vertical section on a plane indicated by the line 2—2 of Fig. 1, as viewed from the left, and of 50 Fig. 3 as viewed from the right.

Fig. 3 is a partial transverse vertical section on a plane indicated by the line 3—3 of Fig. 2 as viewed from the left.

The vehicle-propelling internal combustion engine embodying my invention illustrated in the accompanying drawings has a

cylinder 1 which at its open lower end is connected to a crank case or crank chamber 2 which at one side is closed by a crank case cover 3 as appears in Fig. 1 of the drawings, 60 so that the crank case 2 is closed excepting as to its free communication with the cylinder 1. A usual piston 4 within the cylinder 1 is connected by a connecting rod 5 with a crank 6 on the end of a crank shaft 7. Oil 65 is contained in the lower part of the crank case 2 for lubrication in a usual way, for example, according to the splash system, as is indicated in the drawings, and means involving my invention for automatically replenishing this lubricating oil in the crank case 2 so as to maintain it at a substantially 70 constant level therein will now be described.

An oil reservoir 8 is provided below the crank case 2 and in the construction illustrated in the drawings the oil reservoir 8 is shown as formed integral with the crank case 2. An outwardly opening check valve 9, shown as of the ball type, forms an air outlet from the upper part of the crank case 75 2 into the atmosphere, as clearly shown in Fig. 2. A similar inwardly opening check valve 10 forms an air inlet from the atmosphere into the upper part of the oil reservoir 8, preferably above the level of the oil 80 contained therein, as appears in Fig. 2. The oil reservoir 8 freely communicates with the inside of the crank case 2 at the bottom thereof from a point near the bottom of the oil reservoir 8 and below the level of the 85 oil therein, this free oil-transferring communication being shown as provided by means of an oil tube 11 which projects downward from the bottom of the crank case 2 into the oil reservoir 8 nearly to the bottom 90 thereof, as clearly shown in Figs. 1 and 2. A drainage plug 12 is shown as provided in alignment with the oil tube 11, and it is also to be noted that a larger opening in one side of the oil reservoir 8 is closed by a cover 100 13, appearing in Fig. 1.

From the present stage of description it will now be understood that downward movement of the piston 4 in the engine cylinder 1 will have a compressive effect 105 upon the air contained in the crank case 2 and will expel a portion of this air through the outwardly opening check valve 9 into the atmosphere. It will also be understood that upon the upstroke of the piston 4 in the cylinder 1, a rarefaction or partial vacuum 110 will be produced in the crank case 2, and

as the outwardly opening check valve 9 prevents the entrance of atmospheric air to relieve this rarefaction, the oil from the reservoir 8 will be forced up through the oil tube 11 into the crank case 2, by reason of the substantially atmospheric pressure upon the oil in the reservoir 8 provided through the inwardly opening check valve 10. Upon the return or downward stroke of the piston 4, 10 air will again be forced out of the crank case 2 through the outwardly opening check valve 9, and the oil contained in the bottom of the crank case 2 will not to any appreciable extent return to the oil reservoir 8. 15 through the oil tube or suction tube 11, by reason of the fact that there is substantially full atmospheric pressure upon the oil in the reservoir 8 and also because of the greater sluggishness of the oil contained in the crank case 2 over the lighter and more mobile air contained in the upper parts thereof; this greater sluggishness of the oil of course being due to its viscosity, its inertia, and also to friction in the oil tube 11, and it has 20 been found that no new return valve or check valve for the oil is required to be in control of the oil tube 11.

Were no regulating or controlling means provided, all of the lubricating oil contained 30 in the oil reservoir 8 would be quickly pumped therefrom into the crank case 2, but means now to be described are provided and controlled by the quantity of oil in the crank case 2, and in control of the flow of oil from 35 the oil reservoir 8 into the crank case. An air-transferring port is formed in the bottom of the crank case 2 which also forms the top of the oil reservoir 8, and this air-transferring port is controlled by an upwardly opening float-controlled or float-operated needle valve 14. The air-transferring needle valve 14 is operated by means of a float 15 within the crank case 2 and shown as contained in and guided by a well having an inner wall 40 45 50 55 60 65 16, this well extending below the bottom of the crank case 2, and, in fact, extending to the bottom of the oil reservoir 8, which at this point is shown at a somewhat higher level as appears in Fig 2. The inner wall 16 of the float-containing well is shown as extended upward substantially to the level of the oil in the crank case 2, for effectively guiding the float 15 in the well, but is shown as provided with an opening or port 17 on a level with the bottom of the crank case 2, for the purpose of supplying oil to the well for operating the float therein. The bottom of the float-containing well is shown as closed by means of a screw cap 18 so that the float 15 may be conveniently accessible and may be inserted or removed through the bottom of the well. The oil float 15 is pivotally carried by a float lever 19 the other end of which is pivoted to a yoke 20, the upper end of the needle valve 14 being pivoted as

shown at an intermediary point of the float lever 19. The yoke 20 is carried by the upper end of a screw-threaded adjusting pin or stem 21 which is rotative in the yoke 20 and which extends downward to the outside 70 through a screw-threaded bearing 22 which at this point joins the bottom of the crank case 2 to the bottom of the oil reservoir 8 as clearly appears in Fig. 3 of the drawings, a lock nut 23 being shown as provided for 75 the lower end of the float-adjusting screw stem 21. An opening rendering the needle valve 14 and its valve seat accessible from the outside is shown as provided below and in line with the needle valve 14 and as closed 80 by means of a screw plug 24.

It will now be understood that when the oil in the bottom of the crank case 2 has risen to the desired predetermined level according to and as determined by the adjustment of the float-controlling screw stem 21, the float 15 will rise and will open the air-controlling port which is controlled by the needle valve 14, the needle valve 14 being raised by the float 15. When this port controlled by the needle valve 14 is thus opened, atmospheric air from the upper part of the oil reservoir 8 will pass into the crank chamber 2 and will relieve the partial rarefaction produced therein by the engine piston 4, so that no oil will be forced up through the oil tube 11 from the oil reservoir 8 into the crank case 2, but instead atmospheric air, freely entering the oil reservoir 8 through the inwardly opening check valve 10, will pass through the port controlled by the needle valve 14 and through the crank case and back to the atmosphere through the outwardly opening check valve 9 in the upper part of the crank case 2 as hereinbefore 95 100 105 110 115 120 125 130 described. As soon as the level of the oil in the crank case 2 falls to any substantial extent below a predetermined level, the weight of the float 15 and float lever 19 and of the air-controlling needle valve 14 will close the needle valve 14, preventing any further pumping or transfer of air from the upper part of the oil reservoir 8 into the crank chamber 2, and the pumping of oil from the oil reservoir 8 into the crank chamber 2 will be resumed and will proceed as hereinbefore explained until such time as its level shall rise to the predetermined desired height when again the rising float 15 will raise the needle valve 14 as before and so on, it being understood that the construction and arrangement are such that the oil will be thus pumped from the oil reservoir 8 into the crank case 2 at a slightly faster rate than it is needed therein for lubricating purposes. It will now be clear that the lubricating oil in the bottom of the crank case 2 will be maintained at a substantially constant level or that substantially the same quantity of lubricating oil will at all times

be maintained in the crank chamber 2, such quantity being predetermined and being that which is most desirable for effecting lubrication, which, as hereinbefore mentioned, 5 and as is well understood in the art, is in the construction illustrated in the drawings of the splash type of lubrication. The reserve supply of oil in the oil reservoir 8 may of course be replenished from time to time as 10 may become necessary.

It is obvious that various modifications may be made in the construction illustrated in the drawings and above particularly described within the principle and scope of my 15 invention.

I claim:

1. A lubricating device for an internal combustion engine having a closed crank case, such lubricating device comprising 20 means for expelling air from the crank case, an oil reservoir in oil-transferring communication with the crank case, means for freely admitting atmospheric air into the oil reservoir for forcing the oil therefrom into 25 the crank case, and means controlled by the oil in the crank case in control of the flow of oil from the oil reservoir into the crank case.

2. A lubricating device for an internal combustion engine having a closed crank 30 case, such lubricating device comprising an air-outlet valve from the crank case, an oil reservoir below the crank case, an air-inlet valve for the oil reservoir, oil-transferring communication being provided from a point 35 below the oil level in the oil reservoir to a point within the crank case, and means controlled by the quantity of oil in the crank case in control of the flow of oil from the oil reservoir into the crank case.

40 3. A lubricating device for an internal combustion engine having a closed crank case, such lubricating device comprising an air outlet valve from the crank case, an oil reservoir below the crank case, an air-inlet 45 valve for the oil reservoir oil-transferring communication being provided from a point below the oil level in the oil reservoir to a point within the crank case, a float-controlled air-transferring valve for providing 50 communication from above the oil level in the oil reservoir to the crank case, and a valve-controlling float in the crank case for opening or closing the air-transferring valve according as the oil rises or sinks in the 55 crank case.

4. A lubricating device for an internal combustion engine having a cylinder with a piston therein and having an inclosed crank case, such lubricating device comprising 60 an outwardly opening check valve connecting the upper part of the crank case with the atmosphere for expelling air from the crank case by the compressive action of the engine piston on its return movement, an oil reservoir lower than the crank case, an oil reservoir lower than the crank case, 65

and communicating therewith from a point near the bottom of and below the oil level in the oil reservoir for the transfer of oil from the oil reservoir to the crank case, an air-admitting inwardly opening check valve 70 from the atmosphere into the oil reservoir, and valve means controlled by the quantity of the oil in the crank case for admitting or preventing the entrance of atmospheric air into the crank case for thereby controlling the flow of oil from the oil reservoir into the crank case.

5. A splash type lubricating device for an internal combustion engine having a cylinder and piston therein and having an inclosed crank case, such lubricating device comprising an outwardly opening air-outlet check valve connecting the upper part of the crank case with the atmosphere for expelling air from the crank case by the compressive action of the engine piston on its return movement, an oil reservoir lower than the crank case and freely communicating therewith from a point near the bottom of the oil reservoir and below the level of the oil therein for the transfer of oil from the oil reservoir into the crank case, an air-admitting inwardly opening check valve from the atmosphere into the oil reservoir, a float-controlled air-transferring valve in control of 85 communication from the top of the oil reservoir to the interior of the crank case, and a valve-controlling float in the crank case in control of the air-transferring valve to open or close the air-transferring valve as 90 the oil in the crank case rises above or sinks below a predetermined level.

6. A splash type lubricating device for an internal combustion engine having a cylinder and piston therein and having an inclosed crank case, such lubricating device comprising an outwardly opening air-outlet check valve connecting the upper part of the crank case with the atmosphere for expelling air from the crank case by the compressive action of the engine piston on its return movement, an oil reservoir lower than the crank case and freely communicating therewith from a point near the bottom of the oil reservoir and below the level of the oil therein for the transfer of oil from the oil reservoir into the crank case, an air-admitting inwardly opening check valve from the atmosphere into the oil reservoir, a float-controlled air-transferring valve in control of 100 communication from the top of the oil reservoir to the interior of the crank case, and a valve-controlling float in the crank case in control of the air-transferring valve to open or close the air-transferring valve as 105 the oil in the crank case rises above or sinks below a predetermined level.

7. A lubricating device for an engine having a closed crank-case, such lubricating device comprising means for expelling air from the crank-case, an oil reservoir in com- 110

- munication with the crank-case, and means for admitting atmospheric air into the oil reservoir for forcing the oil therefrom into the crank-case.
5. 8. A lubricating device for an engine having a closed crank-case, such lubricating device comprising an air outlet valve from said crank-case, an oil reservoir lower than said crank-case, an air inlet valve in said 10 oil reservoir, and a passage leading from a point below the oil level in the oil reservoir to a point within the crank-case.
9. A lubricating device for an engine having a closed crank-case, such lubricating device comprising an oil receptacle, a passage leading from a point below the oil level in said oil receptacle into said crank-case, means for reducing the gas pressure in the crank-case below the gas pressure in the oil reservoir, a passage from a point above the oil level in said reservoir into said crank-case,

a valve controlling said passage, and means controlled by the quantity of oil in the crank-case for actuating said valve.

10. A lubricating device for an engine having a closed crank-case, such lubricating device comprising an oil reservoir lower than said crank-case, a passage leading from a point below the oil level in said reservoir into said crank-case, means for reducing the 25 gas pressure in said crank-case below the gas pressure in said oil reservoir, a passage leading from a point above the oil level in said oil reservoir into said crank-case, a valve controlling said passage, a float in said 30 crank-case connected with said valve and arranged to unseat said valve when the oil in the crank-case rises above a predetermined level.

In testimony whereof I have affixed my 40 signature.

JOSEPH F. MERKEL.
